UNITED STATES PATENT OFFICE.

ABRAHAM POSNER, OF BROOKLYN, NEW YORK.

COMBINED ANKLE-STAY AND ARCH-SUPPORT.

1,386,531.

Specification of Letters Patent.

Patented Aug. 2, 1921.

Application filed December 5, 1919. Serial No. 342,710.

To all whom it may concern:

Be it known that I, ABRAHAM POSNER, a citizen of the United States, and a resident of the city of New York, borough of Brooklyn, in the county of Kings and State of New York, have invented a new and Improved Combined Ankle-Stay and Arch-Support, of which the following is a full, clear, and exact description.

10 The object of the invention is to provide a new and improved combined ankle stay or brace and arch support for use as an insert in shoes, and arranged to simultaneously hold up the arch and brace the ankle and to prevent the foot from moving within the shoe thereby giving the desired comfort to the wearer especially when walking.

Another object is to combine an ankle stay and arch support into a single unitary structure, which is stronger and more durable than a brace and a support inserted separately in a shoe.

With these and other objects in view, the invention consists of certain novel features 25 of construction, as hereinafter shown and described and then specifically pointed out in the claims.

A practical embodiment of the invention is represented in the accompanying drawing forming a part of this specification, in which similar characters of reference indicate corresponding parts in all the views.

Figure 1 is a sectional side elevation of a shoe provided with the combined ankle stay 35 and arch support, part being broken out;

Fig. 2 is a perspective view of the combined ankle stay and arch support; and

Fig. 3 is a cross section of the same.

The shoe insert comprises essentially an 40 arch support 10 and an ankle stay or brace 11, of which the arch support 10 is preferably made of a stiff material and comprises a base 12 in the form of a plate, from the inner side of which rises an integral flange 13 extending from the front end of the base 12 to within a distance from the back thereof, as plainly indicated in the drawings. The flange 13 is preferably arched transversely and curved longitudinally to form a 45 firm support for the arch of the wearer's foot with a view to hold up the arch and to prevent the same from falling. The ankle stay 11 is made of a flexible material and preferably comprises a facing 14 of leather 50 and a lining 15 of canvas, the facing and

lining being fastened together at their edges and the facing and lining being provided with a plurality of vertical parallel pockets containing stiffening members 16 of whalebone or the like. The stay is provided at 60 the back with a cut-away portion approximately at the vertical center and extending downward a distance from the top of the stay, as plainly indicated in Figs. 1 and 2.

The stay 11 fits with its lower portion 65 around the back of the base 12 of the ankle support 10 and also along portions of the sides of the said base with the forward lower portion of one side fitting against the rear half portion of the flange 13 of the arch 70 support 10. The lower end of the stay 11 is provided with an inwardly extending attaching flange 20, glued, riveted, or otherwise secured to the under side of the base 12 to securely fasten the arch support and 75 ankle stay together with a view to provide a unitary structure which can be readily inserted into a shoe as plainly indicated in Fig. 1. In practice, the shoe is provided at the inner face of the top with a pocket 25 for 80 receiving the upper end of the stay 11 to permit the user to readily pass the foot into the shoe without disturbing the position of the combined arch support and ankle stay. A covering plate 26 of leather or similar 85 flexible material, is glued or otherwise fastened to the flange 20 and the under side of the rear portion of the plate 12, to assist in holding the flange 20 in place on the plate 12 and to fit snugly onto the insole of the 90 shoe.

It will be noticed that the combined ankle stay and arch support form a unitary structure which can be readily placed in position in a shoe, and when in use it holds up the 95 arch and presses the ankle of the wearer's foot and prevents the latter from moving within the shoe, thereby giving the desired comfort to the wearer especially when walking.

It will also be noticed that the inner side of the ankle stay attached to the flange 13 of the arch support forms practically a continuation of the said flange 13 to provide an exceedingly strong support for the inner side 105 of the foot.

It will further be noticed that an ankle stay and arch support combined in the manner described to form a single structure is considerably stronger and more effective 110

than an ankle stay and an arch support inserted separately in a shoe.

Having thus described my invention, I claim as new and desire to secure by Letters Patent:

1. A shoe insert, comprising a combined arch support and ankle stay, the arch support having a base provided at one side with an upwardly extending flange, the said ankle stay arranged to extend above the ankle and having its lower portion fitting around the back of the base and along portions of the sides of the base with one side fitting snugly on the rear portion of the flange of the support, and means fastening the said arch support and ankle stay together.
2. A shoe insert, comprising a combined arch support and an ankle stay, the arch support being of a stiff material and having a base provided at one side with an integral flange arched lengthwise and curved upwardly, the said stay arranged to extend above the ankle and being of a flexible material and provided with stiffening members, the stay fitting at the lower portion around

the back and parts of the sides of the said base, one side fitting against the rear portion of the said base flange, the said stay being provided at the lower portion with an inwardly extending flange secured to the under side of the said arch support.

3. A shoe insert, comprising a combined arch support and an ankle stay, the arch support being of a stiff material and having a base provided at one side with an integral flange arched lengthwise and curved upwardly, the said stay arranged to extend above the ankle and being of a flexible material and provided with stiffening members, the stay fitting at the lower portion around the back and parts of the sides of the said base, one side fitting against the rear half portion of the said base flange, the said stay being provided at the lower portion with an inwardly extending flange secured to the under side of the said arch support, and a covering plate secured to the said flange and to the under side of the said base.

ABRAHAM POSNER.
